UNITED STATES PATENT OFFICE.

JEAN F. WEBB, JR., OF NEW YORK, N. Y., ASSIGNOR TO THE INTERNATIONAL SIGNAL CO., INCORPORATED, OF NEW YORK, N. Y.

AUTOMATIC SPEED-CONTROL MECHANISM.

1,361,509.

Specification of Letters Patent.

Patented Dec. 7, 1920.

Application filed July 9, 1919. Serial No. 309,740.

To all whom it may concern:

Be it known that I, JEAN F. WEBB, Jr., a citizen of the United States, residing at New York, in the county of New York and State 5 of New York, have invented certain new and useful Improvements in Automatic Speed- Control Mechanism, of which the following is a specification.

My invention relates to mechanism for 10 controlling the speeds of trains, which mechanism is especially designed for use in connection with the air brake system of the train.

In its generic nature the invention has for 15 its object to provide a mechanically controlled valve device for introduction into the air brake system of the train whereby the brakes will be set at predetermined speeds of operation of the train.

20 The specific embodiment of the invention illustrated in the accompanying drawings has been especially designed with the object in view of supplying, at a minimum of cost for both installation and maintenance, a simple, rugged, reliable and efficient mechanical means for limiting the speed of trains to a certain definite maximum, which is predetermined by the railroad management, when track conditions, legal requirements, safety 25 or various other reasons make such a limitation desirable or necessary. Other objects in view in designing this embodiment of the invention are freedom of annoyance to the engineman while in actual service, and reduction, to the point of elimination, of care 30 at the terminals so that no additional skilled labor will be required for its proper maintenance.

35 A further object of the invention is to provide a safety control valve mechanism embodying essentially an air valve movable in one direction by the influence of gravity and in the opposed direction by the influence of centrifugal force converted into rectilinear movement, more specifically the invention 40 providing a reciprocating valve, preferably of the multi-piston type, which is operated by a centrifugal governor mechanism operating against the weight of the valve and 45 such additional weight as may be necessary to effect the desired operation, with provision whereby the amount of the opposing weight may be adjusted to suit the requirements of the particular speed at which the 50 valve is to operate.

A preferred embodiment of the invention designed especially for maximum speed control is illustrated in the accompanying drawings.

The device constituting the illustrated embodiment of the present invention consists of a housing suitably inclosing a series of pistons mounted on a common stem which is raised vertically by the centrifugal action 60 by a pair of governor balls, and is lowered by the gravity of an attached weight as the 65 lifting power of the balls is lessened. In the movements upward and downward, the pistons, which form air chambers inside of the cylinder, connect certain ports, and disconnect other ports, through the cylinder which extends to air chambers in the housing, the latter, in turn, being connected with the air brake system of the train and the atmosphere, thus applying or releasing the air 70 brakes, according to which ports are connected; the size of the weight to be lifted by the balls is variable to suit the variations of the predetermined speed, and the size of the driving pulleys or driving gears may 75 also be varied to suit the variations of the location of the apparatus on the different types of engines.

The invention also consists in the novel construction, combination and arrangement 80 of parts, all of which will be first fully described, specifically pointed out in the appended claims and illustrated in the accompanying drawings, in which:

85 Figure 1 is a diagrammatic view illustrating the manner of use of the invention.

Fig. 2 is an enlarged vertical longitudinal view partly in section of the invention, the parts being in the rest position.

Fig. 3 is a cross section on the line 3—3 90 of Fig. 2.

Fig. 4 is a diagrammatic view illustrating the position of the parts when the maximum speed is reached.

100 In the drawings, like numerals of reference indicate like parts in all of the figures. 50 designates the main reservoir, 51 the equalizing reservoir, 52 the engineer's valve, 53 the train line in which is placed the double heading cock 54, and 55 designates the 105 apparatus constituting the subject matter of the present invention. The apparatus is inserted in the train line, preferably being "looped" into it just after it has passed through the floor of the cab. The particu- 110

lar location of the device itself depends entirely upon the type of the engine on which it is installed and the desired method of driving the drive shaft. 56 designates the whistle or audible signal and 57 designates the pressure retaining valve while 58 indicates the discharge regulator. 59 indicates the drive axle of the engine truck. All of the parts numbered from 50 to 59, inclusive, 10 except the part 55, are of the well-known construction and constitute, *per se*, no part of the present invention.

1 is that portion of the housing which contains the governor balls and the regulating weight, with their coöperating parts. 2 is that portion of the housing which contains the air chambers and into which is fitted the cylinder for the pistons. 3 is the cover for the cylinder and the upper portion of the housing; the sides for the lower portion of the housing are not shown. 4 is a main driving shaft that is journaled near the lower end in a ball-bearing 5, which is tightly fitted in a recess of the housing 1, 20 and at the upper end in the ball-bearing 6, which is tightly fitted in a recess in the cover 3, bushings 7 and 8 respectively being used for such journaling, the bushing 7 being rigidly fastened to the shaft 4 by the pin 9; 25 these ball bearings are not absolutely necessary, but are very desirable. In order to drive the shaft 4 from the axle of the engine drive wheels, or some other suitable portion of the engine, a pulley wheel 10 is fastened to the shaft 4 by the pin 11 so that, 30 through the medium of a spring belt, or some similar device, the shaft 4 will make a certain number of revolutions for each revolution of the engine's drive wheels. Attention is here called to the fact that any desired form of drive may be used, the belt and pulley device being shown in the drawings to facilitate the description. A sliding sleeve 12, whose upper end is journaled in the inner race of ball-bearings 13 and which has two lateral projections 14 and a slot 15, is mounted on the shaft 4, being kept from rotating on the shaft by the pin 16 which is fixedly mounted in shaft 4 and whose ends 35 project through and beyond the slot 15. Two governor balls 17, each having a lifting projection 18 and bifurcated arms 19, are mounted on shaft 4, by pivoting the bifurcated arms 19 on the pin 16, so that the balls 50 are permitted to have a vertical movement when rotated horizontally by the revolutions of shaft 4. Guides 20 are parts of the housing 1, and a sliding weight 21 (which is made in halves that are held together by cap screws 22) is mounted between the guides 20, being supported by the outer race of the ball bearing 13 which is loosely mounted in the slot 23 of the weight 21. This weight 21 is the weight that is varied to suit the variations of the predetermined maximum speed.

By means of slot 24 and lugs 25 engaging with projections 26 and 27 and recess 28 of the piston stem 29, the weight 21 supports the piston stem 29 and transmits its vertical movements thereto. Near its lower end, the 70 piston stem 29 has guides 30 which guide the stem 29 through the circular opening 31 which connects the piston cylinder with the ball and weight chamber. On the upper portion of the piston stem 29, are located the 75 pistons 32, 33 and 34 which are so spaced apart as to form air chambers which will connect or disconnect certain ports in this cylinder wall according to the vertical movements of piston stem 29. These pistons are 80 equipped with piston rings 35 so that the chambers formed between the pistons in cylinder 36 are air-tight. Cylinder 36 is so closely fitted in housing 2 that air chambers 38, 40 and 46 are formed in the housing 85 2. 37 is the port at which the train line air enters the speed control, and is connected with the air chamber 38. Ports 39 connect chamber 38 with the cylinder chamber formed by pistons 34 and 33. When the 90 speed is below the predetermined maximum, the cylinder chamber formed by pistons 34 and 33 is also connected by means of ports 45, with the air chamber 46, which, in turn, is connected with port 95 47 out of which the train line air flows toward the triple valves of the air brake system. Ports 41 connect the cylinder chamber formed by pistons 33 and 32 with the air chamber 40 which, through port 42, is connected with the atmosphere through an audible signal whistle. 43 is a boss limiting the downward movement of piston stem 29, and 44 is a boss limiting the upward movement of the piston stem 29. 48 are cap 100 screws holding the cover 3 on the cylinder 36 and the housing 2. 49 is the rib of the housing dividing the portions 1 and 2. 50' are the tapped holes for attaching the sides of the housing portion 1. 110

Operation.

When at rest and at all speeds lower than the predetermined maximum speed, all of the parts are located approximately as shown 115 in the full lines. After leaving the engineer's valve, the air of the air brake system flows through the cab portion of the train line into port 37 and chamber 38, and through ports 39 into the cylinder chamber 120 between the pistons 34 and 33, and thence through ports 45 into chamber 46 and through port 47 into the remainder of the train line. Chambers 38 and 46, and ports 37, 39, 45 and 47 respectively, have greater 125 areas than the feed port of the engineer's valve, so that there is no restriction of the flow of air. This position of the respective parts, though constantly changing slightly as the drive shaft 4 is being driven faster or 130

slower according to the varying speed of the engine, permits the engineman to handle all of the standard braking apparatus in the accustomed manner without any interference

5 whatever.

When the engine speed exceeds the predetermined maximum speed, the greater number of revolutions of drive shaft 4 increases the centrifugal action of balls 17 which lifts the several moving parts to their respective positions indicated in Fig. 4. Then the air entering at port 37 is held in the cylinder chamber between pistons 34 and 33, while the flow of air in the balance 10 of the train line is reversed so that it enters the air chamber 46 through the port 47, passes through the ports 45 into the cylinder chamber between pistons 33 and 32 and out of this cylinder chamber through ports 15 41 into air chamber 40 and thence through ports 42 and the audible signal to the atmosphere, thereby reducing the train line air pressure and automatically effecting an application of the air brakes. This automatic 20 brake application causes a prompt reduction of train speed, which, in turn, reduces the centrifugal action of the balls 17 and decreases their lifting power, so that the weight 21 gradually lowers the several 25 pistons, and, when the train speed is once more below the predetermined maximum speed, the port 42 to the atmosphere is blanked from the port 47, and the port 47 is re-connected with port 37, so that the normal 30 air connections are re-established, which, in turn, automatically releases the brakes and prevents further speed reduction.

Attention is called to the fact that the device is so designed that the several air 40 pressures in the cylinder chambers always balance themselves so that there is no interference by them with the prompt action and effect of the two natural laws governing the device.

45 While I have illustrated and described the preferred embodiment of the invention as adapted for maximum speed control it is quite obvious that by a slight modification the apparatus can be easily adapted for use 50 in connection with air brake systems equipped with automatic stops. I do not wish it to be understood that I limit the use of the invention to maximum speed control but wish it to be known that the invention 55 may be employed wherever it may be found useful.

What I claim is:—

1. In apparatus of the class described, a valve cylinder having air chambers, ports 60 connecting said air chambers with the interior of the valve cylinder, reciprocating valves in said valve cylinder controlling the passage through said ports, said valves including a hollow open ended stem, weights 65 connected with the stem for moving the

valves in one direction under the influence of gravity and a centrifugal governor device for moving said valves and weight against the action of gravity.

2. In apparatus of the class described, a 70 valve casing including a valve cylinder and air chambers with ports communicating with the interior of said valve cylinder, a valve structure reciprocably mounted in said cylinder for controlling said ports and comprising valves proper and a hollow stem connecting said valves proper, a governor mechanism for operating said valves comprising a governor casing, a weight movable in said casing under the influence of 80 gravity and connected with said valve stem for moving said valves in one direction and a centrifugal ball governor for opposing the action of said weight to move the valves in the opposite direction. 85

3. In apparatus of the class described, a valve casing including a valve cylinder and air chambers with ports communicating with the interior of said cylinder, a valve structure reciprocably mounted in said cylinder for controlling said ports and comprising valves proper and a hollow stem connecting said valves proper, a governor mechanism for operating said valves comprising a governor casing, a weight movable in said casing under the influence of 90 gravity and connected with said valve stem for moving said valves in one direction, a centrifugal ball governor for opposing the action of said weight to move the valves in the 95 opposite direction, said centrifugal ball governor comprising a driving shaft, a sleeve mounted on said driving shaft and engaging said weight, ball arms mounted on said drive shaft and coöperating with said sleeve 100 for moving said sleeve along said drive shaft under the influence of centrifugal force, and means by which said drive shaft may be operated. 105

4. In apparatus of the class described, a 110 casing having a valve chamber and a governor chamber, a port connecting said chambers, said valve chamber including a valve cylinder portion and air chambers with ports communicating with the interior of 115 said cylinder portion, piston valves operable in said cylinder for controlling said ports, a hollow valve stem connecting said piston valves and projecting through the communicating port into the governor chamber, a 120 weight reciprocably mounted in said governor chamber and connected with said valve stem, an operating shaft passing through said chambers and valve stem, centrifugal governor balls mounted on said drive shaft, 125 a sleeve mounted on said drive shaft engaging said weight and governor balls for lifting said weight and valve stem to move the valves against the action of gravity, and means whereby said shaft may be operated. 130

5. The combination with the air brake system of a train, of a speed control mechanism adapted to be connected in the air brake system and comprising a combined air valve and governor mechanism, the latter comprising a multi-piston valve, a valve cylinder having ports in communication with the train line and atmosphere governed

by said multi-piston valve, and a centrifugal ball governor device connected with said valve for operating the valve against the action of gravity, and a weighted member for operating the valve by the action of gravity, and means whereby said centrifugal governor may be operated.

JEAN F. WEBB, JR.
